HIS ATTORNEY

UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed March 19, 1923. Serial No. 625,947.

To all whom it may concern:

Be it known that I, EDWIN E. BARNEY, citizen of the United States, and resident of New Rochelle, in the county of Westchester and State of New York, have invented certain new and useful Improvements in Typewriting Machines, of which the following is a specification.

My invention relates to paper guiding devices for typewriting machines and its object is to produce a new and improved paper guide.

To the above and other ends which will hereinafter appear, my invention consists in the features of construction, combinations of devices and arrangements of parts herein-after described and particularly pointed out in the claims.

My invention will be described in connection with the accompanying drawings wherein,

Figure 1 is a fragmentary sectional view showing part of the carriage and the paper table of a typewriting machine with my invention applied thereto.

Figure 2 is a view corresponding to Fig. 1 but showing some of the parts in different relationships.

Figure 3 is a fragmentary front elevation showing the improved paper guide and its mounting.

Figure 4 is a face view of the paper guide drawn to an enlarged scale, and

Figure 5 is a corresponding end view of the paper guide.

My invention is shown as applied to a platen carriage and paper table construction corresponding with that disclosed in the pending application of Barney & Barr, Sr. No. 582,267, filed Aug. 16, 1922. The platen carriage comprises an inclined rear member composed of a top bar 1, a bottom bar (not shown) and connecting webs 2 which together provide an inclined rear member or plate-like portion 1, 2 having at its ends forwardly extending side bars 3. The carriage or carrier thus constituted carries a rotary cylindrical platen 4. The top bar 1 and the corresponding bottom bar are oppositely grooved to co-operate through anti-friction rollers 5 with fixed grooved guide rails or supports of which the upper one 6 alone appears in the drawing. Mounted on the carriage are a pair of angular brackets, each comprising a foot or base portion

7, an upright portion 8, and, at the top of the latter, an angularly disposed inclined arm or bar-like portion 9. Each bracket is preferably unitary, made of a piece of sheet metal, and is secured to one of the webs 2 by a headed screw 10. The two brackets 7-9 provide a support for a paper table which is formed of two plates or table parts 11 and 12 hinged together so as to afford relative angular movement between the parts. The plate 11 is inclined upward and rearward behind the platen 4 so as to form a bight therewith to receive the paper when it is inserted. The lower end of the plate 11 is formed with fingers 11^a which co-operate with feed roll sections not shown herein but which are disclosed in the previously filed Barney & Barr application aforesaid. Reference may be had to said previously filed application and to the patent of Barr & Barney No. 1,447,639, granted March 6, 1923 for fuller details of the carriage and others parts and mechanism associated therewith than it is deemed necessary to show in the present case. The plate or table part 11 is fixed to the carriage of the machine by headed screws 12 which are threaded into depressions or seats indicated at 9^a in the bracket arms 9. The depressions 9^a accommodate corresponding depressions or counter-sinks 11^b in the surface of the plate 11, enabling the heads of the screws 12 to be countersunk below the surface of the plate 11 so that there may be no projections to interfere with the introduction of paper over said surface. Secured to the back of the plate 11 near its ends as by rivets 13 are upwardly extending arms 14 between which the upper edge portion of the plate 11 is bent or inclined rearward providing a slightly depressed lip or ledge 15. The arms 14 are made of stock sufficiently thick to enable it to be bored out or perforated to provide bearing openings for a pivot rod 16 which extends lengthwise of the plate 11 slightly above and out of contact with the lip 15. The pivot rod 16 is fixed to the upper plate or table part 12 which is provided near its ends with eye members 17 fitting over the rod 16, said rod being fixed to said eye members by cross pins 18. Thus the pivot rod 16 and the plate 12 are secured rigidly together and may be turned or swung on their bearings in the arms 14 so as to afford access from 110

the front of the machine to parts normally covered by the table part 12. Said part 12 is angular in cross section and its upper portion is normally substantially horizontal 5 while its forward inclined portion is in line with the lower plate 11 which wholly supports the plate 12. The lower edge of the plate 12 is curved rearward to provide a lip 19 which corresponds with the lip 15 and 10 is separated from the upper face of the rod 16. The two lips 15 and 19 co-operate with the rod 16 to give a finished appearance to the two-part paper table. The upper end portion of the arms 14 act as stops to limit 15 backward rotation of the plate 12 and assist to maintain it in the normal position illustrated in Fig. 1. From the Fig. 1 position the plate 12 may be swung forward until it is upright as shown in Fig. 2, thus 20 exposing the margin stop mechanism of the machine comprising a stop bar 20, 21 and spring pressed margin stops as 22 adjustable therealong, said bar being mounted on arms 23 which are supported on the upper part 25 of the carriage, all as more fully disclosed in the aforesaid Patent No. 1,447,639.

My novel side edge guide or paper gage shown detached in Figs. 4 and 5 is preferably made of a single piece of thin sheet 30 metal, said guide being designated as a whole by the reference number 24. The body portion 25 of the guide 24 is flat and rectangular and terminates at one end in a triangular upturned portion 26 which is at right-angles 35 to the body portion and serves as the contact face or abutment that co-operates with the side edge of the work sheets. Projecting from the lower edge of the body portion 25 are two fingers, clips or prongs 27 which are 40 curved in correspondence with the curvature of the rod 16. These fingers 27 are spaced apart, and midway between them is a third finger or clip 28 which is oppositely curved to fit over the top of the bar 16. The fingers 45 27 and 28 possess inherently enough spring or resiliency to provide a spring clip or clasp whereby the guide device 34 may be sprung or snapped over the rod or support 16 and frictionally held or maintained thereon. The fingers 27 fit around the front and under 50 side of the bar 16 passing between it and the lip 15, while the intermediate clip or finger 28 passes over the top of the rod and between it and the lip 19. There is sufficient 55 clearance between the clips and the lips 15 and 19 to avoid contact of the parts. The frictional mounting of the guide 24 enables it to be slid along the supporting rod 16 to any desired position and frictionally held 60 in such position. Also the mounting permits rotary movements of the guide 24 on the rod so that said guide may be turned automatically forward on the axis 16 by the table part 12, when said part is swung upward from the Fig. 1 to the Fig. 2 position, or

moved angularly to the part 11. Normally the guide 24 rests with its body portion 25 in contact with the inclined forward portion of the plate 12, so that work sheets when inserted may be passed freely down over 70 the body portion 25 of the guide and the inclined parts of the plates 11 and 12 and into the machine, one of the side edges of each sheet being guided against the contact face or surface 26. When, however, the plate 12 75 is swung forward on its pivotal axis 16 to expose the stops 22 or for any other purpose, the guide 24 will be forced to turn with it and will be carried rotatively to the Fig. 2 position. When the plate 12 is restored to 80 the normal or Fig. 1 position, a slight rearward pressure on the guide 24 will likewise turn said guide back to normal position. The construction is such that the guide 24 85 may be adjusted along the front of the paper table substantially the full length of the rod 16 and of the working length of the platen. Furthermore, the guide 24 may be used at either end portion of its support as a 90 side guide, the contact device or portion 26 co-operating with either side edge of the sheet to position it properly lengthwise of the platen. Of course, when the guide 24 is arranged at the left-hand side, the inner 95 or right-hand vertical face of the contact part 26 will co-operate with the left-hand edge of the work sheet; while when the guide is adjusted at the right, the outer vertical face of the part 26 will provide an 100 abutment for the right-hand side of the work sheet. It is further to be noted that 105 two or more guiding devices such as 24 may be employed and that they may be adjusted on the supporting rod 16 with their upright contact portions close together so that the outer faces of said contact portions may both 110 cooperate with comparatively narrow sheets or strips so as properly to guide said strips into the paper feeding bight of the machine. 115

It will be observed that by my invention, there is provided in combination with the platen and a paper table, comprising two parts capable of relative angular movement, a paper guide which is mounted on the hinge rod that is disposed between the two parts of said table; that the paper guide or side edge guide is readily snapped on and detached from its support; that it is slidably supported on the rod and is also capable of 120 rotative movement thereon; that it is made preferably of one piece of metal; that it normally contacts with the inclined portion of the paper table but is yieldable so that the pivoted device or plate forming part of the paper table may be turned on its axis freely and without obstruction; that the paper guiding device is arranged with its guiding portion at the front face of the table to slide in an opening in the paper table; that said device is supported behind the front face of 125 130

- the table; and that a rod or support is provided in combination with a paper guiding device which is formed with rearwardly projecting spring prongs or clips whereby the device is frictionally attachable to and detachable from its support and clasps the same in such a way that it may be slid along its support and also turned or given rotative movement thereon.
10. The guide is arranged below the top of the inclined portion of the paper table being attached between the top and bottom edges of the inclined portion through the rearwardly projecting spring clips. The opening in the table through which the clips project is so filled by the pivot rod 16 that a practically continuous surface is presented and the paper as it is inserted cannot fall through this opening.
15. Various changes may be made without departing from my invention.
- What I claim as new and desire to secure by Letters Patent is:—
1. In a typewriting machine, the combination of a platen, a two-part paper table, a hinge rod connecting the two parts of said table, and a paper guide on said hinge rod.
  2. In a typewriting machine, the combination of a platen, a two-part paper table, a hinge rod connecting the two parts of said table, and a side edge guide slidable along said rod in the opening between the parts of said table.
  3. In a typewriting machine, the combination of a platen, a supporting rod, and a one-piece side edge guide supported both slidably and rotatively on said rod.
  4. In a typewriting machine, the combination of a platen, a paper table, and a side edge guide having a guiding device at the front face of the table and an attaching device behind the front face of the table.
  5. In a typewriting machine, the combination of a platen, a paper table, a side edge guide having a contact device at the front face of the paper and attaching spring clips projecting backward through an opening in the table, and a support behind the front face of the table with which said clips engage.
  6. In a typewriting machine, the combination of a platen, a pivoted paper table device in rear of the platen, and a side edge guide normally contactive with said paper table device and adjustable therealong, said guide being yieldable so that said paper table device may be turned freely on its axis.
  7. In a typewriting machine, the combination of a platen, a pivoted paper table device in rear of the platen, and a side edge guide normally contactive with said paper table device and adjustable therealong, said guide being yieldable so that said paper
- table device may be turned freely on its axis, said guide being made of a single piece of sheet metal.
8. In a typewriting machine, the combination of a platen, a pivoted paper table device, a pivot rod on which said device is supported, a side edge guide pivoted on said rod 70 and adapted to yield when said paper table device is turned on its axis.
9. In a typewriting machine, the combination of a supporting rod, and a side edge guide provided with spring prongs embracing said rod and frictionally maintaining said guide in adjusted positions thereon. 75
10. In a typewriting machine, the combination of a hinged paper table, a rod, and a side edge guide provided with spring prongs 80 embracing said rod and frictionally maintaining said guide thereon, said guide normally lying against said paper table and being swung pivotally on said rod by said paper table when said paper table is turned 85 on its axis.
11. In a typewriting machine, the combination of a platen, a two-part paper deflector, said parts being spaced apart to provide an opening and being relatively movable, a side guide slidably supported in said opening and adjustable lengthwise of the said paper table, said guide being adapted to yield to permit relative angular movement between the parts of said paper table. 90 95
12. In a typewriting machine, the combination of a platen, a paper table arranged behind said platen and comprising a hinged upper plate having a horizontal portion, a stop supporting bar below the horizontal upper portion of said table, a stop on said bar, and a paper side guide adjustable lengthwise of said paper table at its front side, said guide being adapted to yield when the upper portion of said table is swung on its pivot to 100 expose said stop and said stop bar. 105
13. In a typewriting machine, the combination of a platen, a paper table arranged behind said platen and comprising a horizontally disposed hinged upper portion, a stop bar below the upper portion of said table, a stop adjustable along said bar, a hinge rod on which the upper portion of said table is carried, and a side guide slidable along said hinge rod at the front of said table, said guide being adapted to yield rotatively when the upper part of said table is swung forward to expose said stop bar and said stop. 110 115
- Signed at the borough of Manhattan, city of New York, in the county of New York and State of New York, this 14th day of March, A. D. 1923.
